UNITED STATES PATENT OFFICE.

CHRISTIAN HEILRATH, OF SACRAMENTO, CALIFORNIA.

TRACE-HOLDER.

SPECIFICATION forming part of Letters Patent No. 784,213, dated March 7, 1905.

Application filed July 19, 1904. Serial No. 217,283.

To all whom it may concern:

Be it known that I, CHRISTIAN HEILRATH, a citizen of the United States, residing at Sacramento, in the county of Sacramento and State of California, have invented a new and useful Trace-Holder, of which the following is a specification.

The invention relates to improvements in trace-holders.

10 The object of the present invention is to improve the construction of trace-holders and to provide a simple, inexpensive, and efficient device designed particularly for use on light whiffletrees and adapted to securely retain a trace on the end of the same.

15 A further object of the invention is to provide a device of this character having a hinged hook and adapted to be secured to a light whiffletree by a single fastening device with 20 the latter arranged close to the joint of the hinged hook, so that the force employed for opening and closing the hook will not operate to loosen the fastening device.

25 The invention also has for its object to provide a spring for holding the hinged hook in its opened and closed position and to arrange the spring so that it will be equally effected in either position of the hook and not liable to be clogged by dirt or other accumulation.

30 With these and other objects in view the invention consists in the construction and novel combination and arrangement of parts, hereinafter fully described, illustrated in the accompanying drawings, and pointed out in 35 the claims hereto appended, it being understood that various changes in the form, proportion, size, and minor details of construction within the scope of the claims may be resorted to without departing from the spirit 40 or sacrificing any of the advantages of the invention.

In the drawings, Figure 1 is a perspective view of a trace-holder constructed in accordance with this invention and shown applied 45 to a whiffletree. Fig. 2 is a longitudinal sectional view of the same. Fig. 3 is a detail perspective view of the attachment plate or support upon which the pivoted hook is mounted.

50 Like numerals of reference designate corre-

sponding parts in all the figures of the drawings.

1 designates an approximately semicircular trace-holding hook designed to be arranged on the upper face of a whiffletree 2, as illustrated in the accompanying drawings and having its inner end 3 bifurcated to receive a lug 4 of an attachment plate or support 5. The lug 4 and the sides of the bifurcated inner end 3 of the hook are pierced by a pivot 6, 55 which consists of a pin or rivet. The attachment plate or support is secured to the whiffletree by means of a screw 7, having its head at the lower face of the whiffletree and extending through the same and engaging a 60 threaded opening 8, located at the center of the attachment plate or support 5 and at a point adjacent to the joint of the hinged hook, whereby the plate or support will be securely fastened to the whiffletree and the fastening 65 device rotated in the most effective position to withstand the strain incident to the opening and closing of the hook. In order to prevent the attachment plate or support from accidentally rotating on the threaded end of the 70 screw, it is provided at its ends with inwardly-extending spurs or projections 9, preferably pointed, as shown, whereby they are adapted to be readily embedded in the whiffletree. The screw is adapted to draw the spurs into 75 engagement with the whiffletree and it holds them firmly in such engagement.

The lug 4 is tapered and presents inner and outer rounded inclined faces, which are adapted to be engaged by a head or block 10, having a shank or stem extending into a coiled spring 11, which is housed within a longitudinal opening or socket 12 of the inner end of the trace-holding hook. The socket or opening is curved to conform to the curve of 80 the hook and the spring is correspondingly curved. The head or block forms an engaging member, but the spring may directly engage the lug, as will be readily understood. When the hook is closed, the spring-actuated 85 member engages the outer side of the lug, and when the hook is open the said member engages the inner inclined side or edge of the lug. The outer end of the hook is adapted 90 to fit against the upper face of the whiffletree 95 100

to retain a trace thereon, and it is provided with a projecting portion or grip 13 for enabling it to be readily grasped for opening or closing it. The outer end 14 of the whiffle-
5 tree is adapted to extend through the eye of a trace, the upper portion of which lies within the hook, as will be readily understood.

It will be seen that the trace-holder is exceedingly simple and inexpensive in construction, that it possesses great strength and durability, and that it will enable a trace to be quickly connected with and disconnected from a whiffletree. Furthermore, it will be clear that the fastening device is located adjacent 10 to the joint of the hook and that owing to the arrangement of the spring within the hook itself the base or attachment plate may be made exceedingly small and very short to 15 adapt it for light whiffletrees and to enable it 20 to be secured to the same by a single fastening device.

Having thus fully described my invention, what I claim as new, and desire to secure by Letters Patent, is—

25 1. The combination with a whiffletree, of an attachment-plate provided at its ends with inwardly-extending spurs engaging the whiffle-

tree, a fastening device piercing the attachment-plate at a point between the spurs and securing the former to the whiffletree and retaining the spurs in engagement with the same, and a hook hinged to the attachment-plate adjacent to the fastening device.

2. A trace-holder, comprising a support provided with a lug, a hook pivoted to the lug 35 and provided at its pivoted portion with a socket or opening, and a spring housed within the socket or opening and coöperating with the lug for holding the hook.

3. A trace-holder, comprising an attachment plate or support provided with a tapered lug, a hook pivoted to the lug and having a longitudinal socket, and a coiled spring housed within the socket and provided with means for engaging the opposite faces of the lug for 40 holding the hook in its opened and closed positions.

In testimony that I claim the foregoing as my own I have hereto affixed my signature in the presence of two witnesses.

CHRISTIAN HEILRATH.
